The ornamental design for a cable splitter, as shown and described.

DESCRIPTION

FIG. 1 is a top, front perspective view of the cable splitter showing the new design;

FIG. 2 is a front view thereof;

FIG. 3 is a back view thereof;

FIG. 4 is a left side view thereof;

FIG. 5 is a right side view thereof;

FIG. 6 is a top plan view thereof; and,

FIG. 7 is a bottom plan view thereof.

The broken lines shown represent the portions of the cable splitter that form no part of the claimed design.
